UNITED STATES PATENT OFFICE.

OLIVER L. PERIN, OF CINCINNATI, OHIO.

ALCOHOL-STILL.

SPECIFICATION forming part of Letters Patent No. 244,656, dated July 19, 1881.

Application filed April 23, 1881. (No model.)

To all whom it may concern:

Be it known that I, OLIVER L. PERIN, of Cincinnati, in the county of Hamilton and State of Ohio, have invented certain new and 5 useful Improvements in Alcohol-Stills, of which the following is a specification.

My invention is in the nature of an improvement upon that class of stills for the manufacture of alcohol which are continuous in their 10 operation, and has for its object the construction and arrangement of a float-valve attached to the slop-chamber, which shall automatically open and close and graduate the openings through which the slop passes from the still, 15 to maintain an approximately-uniform head of slop in the slop-chamber; and it consists in attaching to the slop-chamber of the still an independent chamber of suitable form and material containing a float and register-valve, 20 the register or annulus of the valve being suspended from the float to adapt the head of slop carried in the slop-chamber to the requirements of the still.

The register-valve consists of a central cylinder with a closed head, provided with ports or slots disposed around the circumference thereof. A loosely-fitting annulus or ring suspended by a bar or spider from the float travels up and down over the ports and opens the 25 valve more or less to vent the slop and maintain a uniform level in the slop-chamber.

In the accompanying drawings, Figure 1 represents a section of an alcohol-still with my improved float-valve; and Fig. 2 is a perspective view of the register-valve with sections broken away to show the construction thereof.

Similar letters of reference indicate similar parts.

40 A is a spirit-still, consisting of the usual system of vaporizing-chambers and provided with the slop-chamber A' at the bottom thereof.

B is the float-chamber, usually made of wood or copper, to resist the corroding action of the 45 mash or slop, and connected to the slop-chamber by the pipe a.

a' is a pipe also connecting the slop-chamber with the float-chamber to equalize the levels of slop and steam pressures in the two

chambers. This pipe may be dispensed with 50 in all cases where the range of steam-pressures is small.

C is the float, usually of copper, furnished with a stirrup, c, and adjusting-screw c', by means of which the annulus of the register-valve is suspended from the float.

D is the annulus or register of the valve, and E the cylinder provided with ports e e for the exit of the slop. The cylinder of the valve is provided with a flange, e', by means of which 60 it is attached by screw-bolts to the chamber B.

d is a bar placed diametrically across the annulus D, and provided with a nut, d', into which the adjusting-screw c' is threaded, to adjust the position of the annulus relative to 65 the float.

F is a slop-pipe by which the slop is conveyed from the still, provided with a leg or neck, f, attached to the under side or bottom of the float-chamber.

70 G is a stem secured to the upper side of the float, which passes through a stuffing-box in the top of the float-chamber, and is provided with an eye, g, to which the counterpoise H is attached by the rope or chain g'. I is a 75 bracket attached to the still to support the grooved sheaves i i, over which the rope or chain g' passes.

The action of the device is as follows: The 80 float being counterpoised to sink to any desired depth in the slop, the head of slop in the chamber A' is fixed by raising or lowering the annulus D of the register-valve until the lower edge thereof coincides with the lower edges of the ports e e. In this position of the annulus 85 no slop will flow from the still, but with any increase in the quantity of slop in the chamber A' the float C, and, consequently, the annulus D, rises with the increased head and uncovers more or less the ports e e, and permits the excess of slop to vent through the cylinder E and slop-pipe F. Directly the float C descends until the lower edges of the annulus coincide with the lower edges of the ports e e the flow of slop from the chamber A' ceases, and the 90 level in the slop-chamber can be drawn down no lower through the register-valve.

95 In practice the ports e e are always open

more or less, according to the capacity at which the still is being worked; and the slop is passed from the chamber A' as rapidly as it flows from the vaporizing-chambers above.

5 It will be observed, upon inspection of Fig. 2, that the construction of the annulus D is such that it is always in equilibrium as regards the pressure of steam in the slop-chamber and float-chamber, and always imposes a 10 constant load—that of its own weight—on the float C. The slightest change in the level of the slop in the chamber A' is accompanied by a corresponding change in the level of the float and a corresponding increase or diminution of 15 the effective openings in the ports *e e*.

In all forms of float-valves for this purpose heretofore proposed serious practical objections are present, which defeat their pronounced object and unfit them for actual service. Thus in the ball-and-cock valve the action is neither regular nor certain, the friction of the plug in the cock varying with the temperature of the slop, and causing the float to rise higher or sink lower in the slop before the 20 cock is sufficiently opened or closed to vent or check the flow of slop from the still, thereby producing a variable level in the slop-chamber A', and either reducing the level so low as to permit the ventage of steam, or raising it so 25 high as to clog the action of the still. The puppet-valve and float is also very objectionable, in that it requires constant attention to prevent its seating, in which event manual effort is necessary to raise it again, and should it 30 seat at a time when it was not observed the 35

slop would accumulate in the chamber A' and finally back up into the vaporizing-chambers of the still, and render so many chambers as were charged with the slop temporarily useless.

With my device no attention is requisite, the register-valve automatically responding to any change, however slight, in the quantity of slop in the chamber A'.

Having described my invention, what I claim 45 is—

1. In continuous spirit-stills, the automatic float-valve consisting of the float C, annulus D, and cylinder E, having ports or perforations *e e*, substantially as and for the purpose 50 described.

2. The combination of the chamber B, float C, stirrups *e*, adjusting-screw *e'*, and annulus D, substantially as and for the purpose described.

3. The combination of the float-chamber B, float C, stem G, counterpoise H, rope or chain *g'*, and sheaves *i i*, substantially as and for the purpose described.

4. The combination, with the spirit-still A, 60 of the float-chamber B, float C, and register-valve consisting of the elements D E and *e e*, substantially as and for the purpose described.

In testimony whereof I have signed my name to the foregoing specification in the presence 65 of two subscribing witnesses.

OLIVER L. PERIN.
